SMOKING PIPE

Charles C. Cohee, Indianapolis, Ind.

Application April 5, 1937, Serial No. 135,010

3 Claims. (Cl. 131—12)

The object of my invention is to produce a smoking pipe, of simple, relatively inexpensive construction which will retain within itself, such moisture as is generated as a result of the burning of the tobacco, and as is injected thereinto as saliva by the smoker, in such manner as to practically prevent nicotine-contaminated liquid from passing into the mouth of the smoker.

The accompanying drawing is a slightly magnified section longitudinally of the stem, and illustrates embodiments of my invention:

Fig. 1 is a section of a straight stem pipe; and Fig. 2 a section of a drop stem pipe.

In the drawing 10 and 11 indicate, respectively, the bowl and integral stem of a pipe. The outer end of the stem is counterbored at 12 to receive the enmasaled end 13 of supplemental stem, or bit 14. Stem 11 is bored, at 15, from the bottom of the counterbore into the bowl and within this bore 15 is mounted, conveniently permanently, a tightly fitting metal tube 16 the outer end of which is spaced from the inner end of end 13 of stem 14, and the inner end of which preferably extends to the axis of the bowl.

Immediately below bore 15, stem 11 is bored at 17, to form a cul-de-sac, or closed-end pocket, for the removable reception of the closed inner end of metal tube 18 which is mounted in bore 19 which extends axially through stem 13—14, the outer end of tube 18 preferably extending close to the mouth end of bore 19. The inner end of bore 19 is enlarged at 19' over the top of tube 18 and registering with this counterbore is a perforation 20 through the upper part of tube 18 into the interior thereof, thus dividing tube 18 into a blind pocket or reservoir end R and a smoke outlet end C.

The position of perforation 20 depends somewhat upon the distance between the bowl and the mouth end of stem 14, but in any event it should be spaced from the outer end of tube 16 (or bore 15) so that any saliva entering tube 18 in quantities sufficient at any one time to fill the diameter of the bore of said tube, and thus having a tendency to flow outwardly through the perforation 20, may sink into the inner end of the counterbore 12. In use, moisture rarely gathers in this counterbore. Perforation 20 should be far enough away from the outer end of tube 18 to insure condensation of moisture from the smoke at an effective distance from the mouth so as to permit the condensate to flow back into reservoir R rather than to be sucked into the user's mouth, having in mind the fact that the farther away perforation 20 is from the sealed in-

ner end of tube 18, the greater will be the capacity of reservoir R. I believe that, in a pipe of the relative portions shown in the drawing, perforation 20 may be effectively placed about midway between the bowl and the mouth end of stem 13—14. The bore of tube 18 should be large enough to receive an ordinary pipe-cleaner swab.

In use, the smoke is drawn from the outer end of tube 16, enters tube 18 through perforation 20 and passes into the mouth of the user. Condensation from the smoke occurs adjacent perforation 20, mostly within tube 18 and flows into the blind-end reservoir end R of said tube. Saliva entering tube 18 will trickle into said reservoir end R and, because of the gap between perforation 20 and the outer end of tube 16, will not pass through 20 so as to produce "frying" in the bowl.

As a rather profuse "wet" smoker, I have found, in an extended use of a pipe constructed as described above, that a perfectly dry, cool smoke is afforded and that no nicotine-contaminated liquid enters the mouth.

After use tube 18 may be readily freed of liquid either by a snappy shaking of the pipe with stem inverted, in a manner well known to smokers, or by swabbing with a cleaner, either with or without separation of stem 13—14 from the bowl, and tube 16 may be readily swabbed upon removal of stem 13—14, tube 18 lying loosely in bore 17 and coming out with stem 13—14.

Any slug of liquid in reservoir R cannot be sucked from the reservoir because of the intermediate perforation 20 and the closed inner end of tube 18.

I claim as my invention:

1. A smoking pipe comprising a bowl and separable bored stem, a metal tube mounted in the bore of the stem and having a closed inner end and a perforation through its top side intermediate its open end and its inner closed end with a substantial length of said closed end lying within a blind pocket formed in the main body of the pipe, a comparatively short nicotine pocket surrounding said tube between the bowl and said perforation, the upper region of said nicotine pocket communicating respectively with the bowl and the said perforation.

2. A smoking pipe comprising a bowl and bored stem, a metal tube mounted in the bore of the stem having a closed inner end and a perforation through its top side intermediate its outer open end and its inner closed end, a substantial length of said closed end lying within a blind pocket formed in the main body of the pipe, a

comparatively short nicotine pocket surrounding said tube within the main body of the pipe at a point intermediate its closed end and said perforation, a smoke conduit leading from the bowl to the bowl end of the upper region of said pocket, and a second smoke conduit leading from the upper region of the bit end of said pocket to said perforation.

3. A smoking pipe comprising a bowl and bored 10 stem, a metal tube mounted in the bore of the stem having a closed inner end and a perforation

through its top side intermediate its outer open end and its inner closed end, a comparatively short nicotine pocket surrounding said tube within the main body of the pipe only at a point intermediate its closed end and said perforation, a conduit leading from the bowl to the bowl end of the upper region of said pocket, and a second smoke conduit leading from the upper region of the bit end of said pocket to said perforation, and a metal tube in said first-mentioned conduit. 10
